UNITED STATES PATENT OFFICE

CLAYTON POTTS AND WILLIAM S. MINTER, OF INDIANAPOLIS, INDIANA, ASSIGNEES TO
C. & G. POTTS COMPANY, OF INDIANAPOLIS, INDIANA, A CORPORATION OF INDIANA

BRICK MOLD RAPPING MECHANISM

Application filed February 7, 1929. Serial No. 338,105.

This invention relates generally to the art of brick making and in particular to means applied to a brick molding machine for rapping the brick molds and has for its principal objects the provision of such means that may have its moving parts largely concealed and covered up to prevent excessive wear due to clay and foreign matter working down through the machine; that may be adjusted quickly to vary the blow of rapping; that will not interfere with the movements of an operator about the machine and not be a source of danger to him; and that will cause each mold to receive a plurality of blows with the minimum of movement of the associated parts.

Other objects will become apparent at once to those versed in the art in the following description of the one particular form of the invention as shown by the accompanying drawings, in which

Fig. 1 is a perspective view of the forward end of a brick molding machine embodying the invention;

Fig. 2, a fragmentary top plan view of the molding table;

Fig. 3, a side elevation of the table;

Fig. 4, a longitudinal vertical section on the line 4—4 in Fig. 2;

Fig. 5, a transverse vertical section on the line 5—5 in Fig. 3;

Fig. 6, a transverse vertical section on the line 6—6 in Fig. 3;

Fig. 7, a longitudinal vertical section on the line 7—7 in Fig. 6;

Figs. 8, 9, and 10 various relative positions of the hammer latch;

Fig. 11, a top plan view on a reduced scale of the table with molds thereon;

Fig. 12, a detail of a spring seat; and

Fig. 13, a vertical section on the line 13—13 in Fig. 10.

Like characters of reference indicate like parts throughout the several views in the drawings.

Referring first to Figs. 1-4, the table 15 which is carried in the machine to support molds thereon as the clay is pressed into them, is provided with ears 17 and 18 on one side to pivotally support the hammer arm

19 therebetween so that the arm may swing in a horizontal plane. On the other side of the table, the similar ears carry the hammer arm 20 to swing in substantially the same horizontal plane as that of the arm 19.

From the arms 19 and 20, the legs 21 and 22 extend respectively inwardly under the table 15 for a distance and on their inner ends on the back faces thereof, are bolted the brackets 16 and 23, each of which has a forwardly downwardly and outwardly curved cam 24 and 25 respectively extending therefrom (Figs. 8, 9, and 10).

The arms 19 and 20 are each tied respectively by the links 26 and 27 to the rocker arms 28 and 29. These rocker arms 28 and 29 are pivotally attached to the table 15 near its forward end and each arm extends rearwardly under the table and bowing outwardly from the longitudinal center line of the table. By rocking each rocker arm 28 and 29 toward the table longitudinal center line the hammer arms 19 and 20 are pulled inwardly toward the sides of the table.

The rocker arms 28 and 29 are normally swung toward the center line by means of the respective springs 30 and 31. Each of these springs has a head 32 fitted in their inner end, and this head has a slotted end into which the rocker arm may freely enter.

A vertical pin 33 (Fig. 12) passes through the slotted end and the rocker arms have notches 34 therealong into which the pins 33 may enter. The opposite or outer ends of the springs 30 and 31 are carried on the seats 35 and 36 projecting inwardly from the longitudinal sides of the table 15. A bar 37 extends outwardly within the springs from each inner head 32 for a distance as a means for preventing the buckling of the springs when compressed.

Each of the outer spring seats 35 and 36 has a screw-threaded shank 38 extending therefrom out through the table side and screw-threadedly engaged through a spur gear 39 (Fig. 6). The shank extends on through the gear and has an outer end square in cross section for a substantial length slidingly guided through a collar 40 having an outer cylindrical surface and which is normally

held against rotation by means of the set screw 41. A spur gear 42 is in mesh with the gear 39 and has a shaft 43 extending therethrough in a fixed relation therewith. This shaft extends from one side to the other of the table 15 so that both gears 42 (one on each side of the table within the respective housings 44) are revolved by turning of the shaft. A crank 45' (Figs. 3 and 6) fitted on the projecting end of the shaft 43 is employed as means of revolving the shaft 43 to revolve the gears 39 whereby the shanks 38 are advanced or withdrawn through the gear 39—one of the shanks being threaded left handed and the other right handed so that the seats 35 and 36 will be simultaneously carried toward each other or simultaneously away from each other upon rotation of the shaft 43. It is, therefore, to be seen that the compression 20 of the two springs 30 and 31 may be adjusted at will.

While both springs 30 and 31 may be simultaneously compressed or extended as above described, each spring may be independently 25 adjusted as to compression by permitting the shaft 43 to remain stationary, removing the set screw 41 from engagement with the collar 40 and there turning the shank 38 by its outer square end projection which will cause 30 the collar 40 to revolve therewith and cause the shank 38 to travel longitudinally through the gear 39 to the desired position whereupon the collar is again secured by running the set screw 41 against it.

35 Rubber bumpers 45 and 46 act as stops limiting the extreme travel of the hammer arms 19 and 20 toward the table sides. A slider-bar 46' is slidingly guided and retained centrally longitudinally along the under side of 40 the table 15 and carries a head 47 bolted to its forward end, on the top side of which are two rollers 48 and 49 each carried on a vertical axis and adapted to contact and roll along the inner edges of the rocker arms 28 and 29 as the head 47 may be reciprocated. The travel of the head 47 is so determined and the rocker arms 28 and 29 are so curved in 45 relation thereto that forward travel of the head will permit the arms to swing in toward each other through pressure of the springs 30 and 31, while rearward travel will cause the rollers to contact and spread the arms apart to overcome the springs 30 and 31.

50 On the respective sides of the head 47 are pivotally secured the dogs 50 and 51, the dogs being free to swing vertically about horizontal pins 52 (Fig. 4) and being limited by the set-screws 53 on the head from swinging from below substantially a horizontal plane thereacross.

55 On the forward face of each of the dogs 50 and 51 are bolted the respective plates 55 and 56. Each of these plates is formed so that, as the head 47 is moved backwardly and 60 the hammer arms 19 and 20 thereby are car-

ried outwardly, the plates 55 and 56 contact the forward faces of the respective cams 24 and 25, and by reason of the curvature of the cams, the plates slide upwardly thereover and then drop down behind the cam brackets 16 and 23 as the head 47 comes to the end of its stroke. 70

Now when the head 47 is moved forward, the plates 55 and 56 are brought up snugly against the back faces of the brackets 16 and 23 and a lug 57 projecting forwardly from the under edge of each plate 55 and 56 (Figs. 8, 9, 10, and 13) comes under the brackets to prevent the plates from moving vertically. Continued travel of the head forward causes 80 the legs 21 and 22 to be carried forwardly and outwardly to swing the hammer arms 19 and 20 outwardly accordingly against the compression of the springs 30 and 31 until the plates slip off the ends of the brackets 16 and 23 whereupon, the legs 21 and 22 being free, the hammer arms 19 and 20 swing sharply inwardly toward the sides of the table 15. The brackets 16 and 23, and plates 55 and 56 are so arranged, that one plate will 85 slip past its respective bracket before the other plate slips past its respective bracket, so that both hammer arms 19 and 20 do not swing in simultaneously, but quickly one following the other. 90

95 The head 47 is not reciprocated continuously, but in timed relation to the movement of molds (Fig. 11) along the table 15.

The head 47 is moved forwardly at the correct time and then rearwardly where it remains for a time interval before moving ahead again. This action is obtained by means of the links 60 and 61 interconnecting the bar 46 near its rear end with the lower arms 62 which are fixed on the shaft 63. This shaft 63 is rocked intermittently by the connecting rod 64 from the wheel 65, by reason of the slotted end of the rod 64 engaging the crank pin on the crank 66 (Fig. 1). 100

105 Referring now particularly to Figs. 1 and 11, molds 67, 68, 69, 70 are inserted consecutively under the press to be filled with clay and are moved forward one at a time over the table 15 to come between the guides 72, 73, 74 and 75 extending vertically above 110 the table top from along its sides. The forward ends of the hammer arms 19 and 20 carry heads or blocks 76 and 77 bolted thereto which pass between the respective guides. The molds are stopped on the table so that 115 the line 78 between two adjacent molds comes between the openings between the guides, whereby, when the hammer heads strike, the heads will strike the corners of the two molds 68 and 69 and not just one 120 mold alone. 125

The molds are slightly less in width than the distance between the guides on the respective sides of the table so that the molds may be moved slightly sideways over the ta- 130

ble between the guides. Now as one hammer head 76 strikes the corners of the molds 68 and 69, the molds will be driven across against the opposite guides to receive thereby a second blow, whereupon the hammer head 77 strikes and knocks the molds back across to receive a fourth rapping.

Each corner of each mold being subjected to a blow from a hammer head, each mold, 10 therefore, in effect receives eight rappings before passing entirely beyond the guides.

The molds are moved forwardly over the table 15 in timed sequence by a mechanism actuated from the shaft 63, said mechanism being well known to those versed in the art 15 and not here forming a part of our invention.

It is to be noted that loose particles of clay 20 may drop down through between the rollers 80 before the molds are rapped and that the moving parts actuating the hammer arms are completely covered over by the solid table top (Fig. 1.).

While we have here described and shown 25 our invention in one particular form, it is obvious that many structural changes may be made from that form without departing from the spirit of the invention, and we, therefore, do not desire to be limited to that 30 precise form nor any more than may be required by the following claims.

We claim:

1. In a mold rapping device, a table adapted 35 to carry molds thereon, mold arresting means, a hammer on each side of the table movable in relation thereto, means normally moving said hammers toward the table, means overcoming said first means for holding said hammers outwardly from the table, and actuating means alternately releasing said hammers from said second means to strike the molds and knock them in alternate opposite directions against one of the 40 arresting means.

2. In a mold rapping device, a table adapted 45 to carry molds thereon, a hammer on each side of the table pivoted to swing in relation thereto mold guides on each side of the table, said guides being spaced apart a distance slightly greater than that of the width of the molds passing therebetween, said hammers being adapted to strike said molds from their sides and knock them against said guides.

3. In a mold rapping device, a table adapted 50 to carry molds thereon, a hammer on each side of the table pivoted to swing in relation thereto, mold guides on each side of the table, said guides being spaced apart a distance slightly greater than that of the width of the molds passing therebetween, said hammers being adapted to strike said molds from their sides and knock them against said guides, and means for withdrawing said 55 hammers from the molds and causing the

hammers to strike consecutively one after the other.

4. The method of rapping molds, consisting of intermittently moving a plurality of molds in contact one with the other, moving each mold successively and suddenly in a lateral direction and suddenly arresting it and then moving the same mold suddenly in the opposite direction and suddenly arresting it during intermissions of the first movement. 70

5. The method of rapping molds, consisting of intermittently moving a plurality of molds in contact one with the other, successively moving an adjacent corner of each pair of molds suddenly in a lateral direction and suddenly arresting them, and then moving the corner at the opposite side and end of one of that pair and a next following mold suddenly in the opposite direction and suddenly arresting them, all during intermission periods in the first movement of the molds. 75

6. In a mold rapping device, a table, a pair of hammer arms each pivoted at the side of the table to swing theretoward, a leg extending from each arm to under the table, means normally tending to force the arms inwardly, a member under the table adapted to be moved to overcome said means and carry said arms outwardly from the table, and dogs associated with said member to contact said legs whereby said legs are rocked to carry the arms outwardly from the table then permit the arms to spring back toward the table. 80

7. In a mold rapping device, a table carrying molds thereon, a hammer arm pivoted on each side of the table adapted to swing at successive moments and knock the molds on diagonally opposite corners in opposite directions, springs normally tending to swing the arms toward the table and means for adjusting the force of the hammer blow. 95

8. In a mold rapping device, a pair of hammers, a pair of springs normally moving said hammers, a seat at the end of each spring, a screw-threaded shank extending from each seat, a gear screw-threadedly receiving the shank therethrough, means for normally preventing the rotation but permitting longitudinal travel of the shank, and means for simultaneously revolving each of said gears, said gears being held against longitudinal travel in relation to each other. 100

9. In a mold rapping device, a pair of hammers, a pair of springs normally moving said hammers, a seat at the end of each spring, a screw-threaded shank extending from each seat, a gear screw-threadedly receiving the shank therethrough, means for normally preventing the rotation but permitting longitudinal travel of the shank, and means for simultaneously revolving each of said gears, said gears being held against longitudinal travel in relation to each other, and means for releasing said first means whereby either one of said shanks may be individually re- 105

volved to be carried longitudinally through the gear of the other shank.

10. In a mold rapping device, a table, a hammer arm pivoted at each side of the table, a pair of spaced apart rocker arms under the table, a link between each rocker and the adjacent hammer arm, a spring normally pressing each of the rocker arms inwardly to carry the hammer arms toward the table, and a bar reciprocating under the table having a head extending between said rocker arms, said rocker arms being bowed whereby said head may spread said rocker arms apart upon travel of the bar to carry said hammer arms away from the table, and means associated with said bar permitting said hammer arms to fly back toward the table.

11. In a mold rapping device, a table, a hammer arm pivoted at each side of the table, means normally carrying the hammer arms toward the table sides, a leg extending to under the table from each of said arms, a reciprocating bar under the table, a cam on the inner end of each leg having an upper face curving downwardly from the end of the leg, a dog pivoted on each side of the said bar adapted to rock freely in a vertical plane, stops limiting the travel of the dogs downwardly, said bar being capable of being moved whereby said dogs contact said cams, ride upwardly thereover and drop therebehind and the reverse travel of the bar causes said dogs to bear against and rock said legs outwardly and then release them.

12. In a mold rapping device, a table, a hammer arm pivoted at each side of the table, means normally carrying the hammer arms toward the table sides, a leg extending to under the table from each of said arms, a reciprocating bar under the table, a cam on the inner end of each leg having an upper face curving downwardly from the end of the leg, a dog pivoted on each side of said bar adapted to rock freely in a vertical plane, stops limiting the travel of the dogs downwardly, said bar being capable of being moved whereby said dogs contact said cams, ride upwardly thereover and drop down therebehind and the reverse travel of the bar causes said dogs to bear against and rock said legs outwardly and then release them, and said dogs having lugs thereon engaging under said leg ends.

13. In a mold rapping device, a table, a hammer arm pivoted at each side of the table to swing theretoward, a pair of rocker arms under the table, links interconnecting the hammer arms with the rocker arms, springs normally pressing the rocker arms to swing the hammer arms toward the table sides, a bar adapted to be reciprocated under the table, a head on the bar adapted to spread said rocker arms apart upon travel of the bar, a leg extending from each hammer arm to under the table, and dogs on the head

adapted to contact the legs whereby reverse travel of the bar will carry the dogs first against the legs and then slide them past to rock the legs to spread the hammer arms outwardly and then permit them to fly inwardly.

In testimony whereof we affix our signatures.

CLAYTON POTTS.
WILLIAM S. MINTER.
